DINNER PLATE OR SIMILAR ARTICLE

Richard H. Garvin, Syracuse, N. Y., assignor to Onondaga Pottery Company, Syracuse, N. Y., a corporation of
New York

Application December 14, 1955, Serial No. 39,329

Term of patent 14 years

(Cl. D44—15)

The drawing is a plan view of a plate of conventional configuration showing my new design.

I claim:

The ornamental design for a dinner plate or similar article, as shown and described.
